US00D962943S

(12) **United States Design Patent** (10) Patent No.: **US D962,943 S**
Peng et al. (45) Date of Patent: ** Sep. 6, 2022

(54) **SCANNER**

(71) Applicant: **Avision Inc.**, Hsinchu (TW)

(72) Inventors: **Chao-Yu Peng**, Hsinchu (TW);
Shao-Lan Sheng, Hsinchu (TW)

(73) Assignee: **AVISION INC.**, Hsinchu (TW)

(**) Term: **15 Years**

(21) Appl. No.: **29/772,797**

(22) Filed: **Mar. 4, 2021**

(30) **Foreign Application Priority Data**

Sep. 7, 2020 (TW) 109305071

CLAIM

The ornamental design for a scanner, as shown and described.

DESCRIPTION

FIG. 1 is a top perspective view of a scanner showing our new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view of the scanner shown in an environment of use.

The broken lines illustrate unclaimed features of the scanner that form no part of the claimed design.

1 Claim, 5 Drawing Sheets
